SHINGLE

Joseph L. Killingsworth, Des Moines, Iowa

Application March 13, 1948, Serial No. 14,769

5 Claims. (Cl. 108—7)

1

The present invention relates to a shingle to be applied as a roof covering; a shingle used as a siding cover or for any covering purpose to make a structure water tight and weather proof. More particularly, it relates to an interlocking shingle, made of any suitable material and when laid on a roof, the shingles interlock to give a covering forming a series of hexagonal designs.

In roof coverings, shingles have been used with great success for many years. Interlocking shingles have been used heretofore and interlocking shingles that give a hexagonal design effect on a roof. The hexagon design effect makes a nice looking roof, pleasing to the eye and is desirable from the point that it improves the looks of a structure. A hexagonal design roof has another advantage in that water coming down over the roof runs away from side lap leaks and has little chance to get under the shingle and to the nail hole points to leak through the roof sheathing. This tends to give a more positive tight roof.

It is an object of the invention among others to provide an interlocking shingle that gives a hexagonal design on a roof when assembled with other shingles and laid on a roof; an interlocking shingle that allows assembly without binding; allows accurate lining up over the sides of assembled shingles to form a hexagon and a shingle assembly that is held fast even though a wind-storm tends to lift the shingles; a shingle when adjoining shingles are attached that requires only one attaching means with said attaching means being so protected that leakage can never occur through holes in the shingles made by the attaching means; a shingle possessing aligning means to indicate to an applicator that the shingle being assembled is in place with regard to the already assembled shingles; a shingle that may be cut or stamped from a blank of material without any waste in cutting or stamping; a shingle wherein the installation cost is held to a minimum and is much cheaper to install than any known shingle today; a shingle that makes a durable and long lasting covering when applied; a shingle simple and economical to manufacture; and a shingle that can easily be replaced in an existing covering if need arises for repair.

With the foregoing and other objects in view, the invention will be more fully described hereinafter and will be particularly pointed out in the claims appended hereto.

In the drawings, wherein like symbols refer to like or corresponding parts throughout the several views:

2

Figure 1 shows a sheet of material of a certain width and the manner of cutting the shingles from the sheet of material.

Figure 2 is a plan view of the shingle shown in Figure 1.

Figure 3 is a plan view showing the shingle of Figure 2 laid in several courses and with some of the covered portions of the shingle shown in dotted line.

10 The shingle has a top portion 21 and a bottom portion 22 with a locking ledge portion 23 separating the top portion 21 from the bottom portion 22. The distance from the bottom of the shingle to the locking ledge portion is 9 inches. 15 Locking tabs 24 and 25 extend from each side of the lower end of the bottom portion 22 of the shingle. The shingle has a projecting portion 26 and tab 27 extending outwardly from each side of the top portion 21 of each shingle. The projections 26 and tabs 27 on adjoining assembled shingles overlap when the shingles are assembled with the overlapping tabs 27 providing nailing points to attach the assembled shingles to a roof. The overlapping projections 26 eliminate any possible 20 space between adjoining shingles below the water-line of adjoining shingles when assembled. The shingles now in common usage abut at the top portion of adjacent shingles. In the present structure the overlapping projections 26 allow a little spreading between the adjacent shingles 25 without eliminating coverage over a limited area between top portions of adjacent shingles.

The locking ledges 23 extend downwardly for a substantial distance, at an angle to a vertical line 20—20 through the center of the shingle along its length. The angular tilt of the locking ledge 23 forms a wedging surface to receive locking tabs 24 or 25. If wind pressure gets under the shingle and tends to lift the shingle, the locking tabs 24 or 25 ride on the locking ledges 23 and continued outward movement of the locking tabs 24 or 25 on locking ledges 23 makes a tighter wedging between the locking tabs 24 and 25 and locking ledges 23 and thus prevents removal of the locking tabs 24 and 25 from the locking ledges 23 and to prevent disassembly of the shingles. The innermost ends 32 of the ledge portions 23 extends a distance equal to the thickness of the material from which the shingles are cut, above a line 33—33 passing through the center of the locking ledges 23 with the line 33—33 being perpendicular to the line 20—20 through the center of the shingle along its length. The outermost ends 34 of each locking ledge 23 extends below the line 33—33, a distance equal to

the thickness of the material from which the shingles are cut.

A side wall 35 on the lower portion 22 extends upwardly and outwardly to a point 36 below the locking ledges 23. The side wall then extends upwardly and inwardly as at 37, until it reaches the locking ledge portion 23.

The material from which the shingle is made does not enter into the novelty of the invention and the shingle may be made of sheet metal or a flexible material and serve with equal success as a covering. Figure 1 shows a sheet of material from which the shingles are cut, which sheet of material may be sheet metal of any metal suitable for a roof covering or any other covering. The sheet of material is 36 inches wide and of any length desired. The separate shingles can be stamped from the sheet of material as shown in Figure 1 without any waste of sheet material. If the shingles are to be made from a felt asphalt base material coated with slate or rock granules, the separate shingles may be cut, in a well known manner in this art, from a sheet of material 36 inches in width and of any length without any waste of material in the cutting. This is very important in manufacture or cutting of the shingles, because waste material adds to the cost of the shingles and further the waste material cannot be salvaged for any purpose or use. Further, waste material must be removed as it collects and a further expense is incurred in that additional men are required to remove the waste material. Cutting the shingles without waste is a definite advantage in that it conserves material and reduces cost of manufacture.

In applying the shingles as shown in Figure 3, the first course is established along the lower edge of a roof with the lower portion 22 of each shingle being cut off to establish the base line 38 along the lower edge of a roof, a practice well known to applicators in getting the covering started up a roof. The shingle 39 is in place on the roof with shingles 40 and 41 assembled to shingle 39 to make the next course up the roof. The locking tab 24 on shingle 41 and the locking tab 25 on shingle 40 fit under shingle 39, as shown in dotted line in Figure 3 and ride against locking ledges 23. The shingle 40 with the locking tab 25, is pulled upwardly until the innermost end of locking tab 25 contacts side wall portion 37 after which shingle 40 is pulled upwardly until the innermost end of locking tab 25 contacts the innermost end 32 of the locking ledge 23 of the shingle 39 when the assembled shingle 40 is in place. The innermost end 32 of the locking ledge 23 allows accurate lining of shingle 40 to line up the sides for the hexagon and to be in approximately proper place for attaching when shingle 41 is assembled. Shingle 41 now has locking tab 24 assembled with locking ledge 23 on the other side of shingle 39 in the same manner as just described for shingle 40, and shingles 40 and 41 are now pulled into position where tabs 27 and projections 26 overlap. The applicator then drives nail 42 through overlapping tabs 27 and through the top portion of shingles 39 into the roof sheathing and roof. One nail therefore goes through three shingles 39, 40 and 41 to hold the roof covering assembled on the roof.

The projections 26 extending from the upper portion 21, merge with the upper portion at points 44 and the tabs 27 merge with the upper portion 21 at the same points 44. In assembling, the points 44 give an applicator a visible means of aligning an applied shingle with those already

in place. When the points 44 align with the top edge 43 of a lower course, the applicator is assured the shingle being applied is in place. Further the points 36 serve as a second aligning means in that the shingle being applied is in proper position with relation to the shingles already applied when the points 36 align with the bottom edge 38 of each shingle being applied.

The side wall 35 of each shingle aligns with the upwardly and inwardly extending side wall portion 37 when the shingles are assembled to form the side walls of the hexagon design when the shingles are on a roof. The side wall 37 allows the shingles to be interlocked and aligns with side wall 35 to eliminate any break in the side walls of the hexagon design on the roof.

As the courses advance on the roof, each course advances the roof covering upwardly 9 inches. The attaching means 42 for adjacent shingles is so situated when the covering is completed, that water running down over the covering can never get to the attaching means 42 to leak through the holes in tabs 27. The sides forming the hexagon always direct any water flowing away from the attaching means 42 and the water if it did get under the shingle would have to travel a maximum distance before reaching a nail hole. There is little or no likelihood of wind driving water under the bottom portions of the shingles and having sufficient force to drive the water to the holes made by the attaching means 42 in view of the secure interlock between adjoining shingles and the distance the water would be forced to travel to reach the attaching means 42.

The nail 42 goes through three shingles when the shingles are assembled which thus gives a more secure joint. The overlapping projections 26 on adjoining shingles are advantageous and important in that they prevent water getting to any point of leakage when the shingles are assembled on the roof. As will be seen the overlapping projections 26 of shingles 40 and 41 are above a possible water line 43 when shingles 40 and 41 are assembled. The projections 26 are triangular in shape and the apexes of the overlapping triangles 26 come to a common point. The tabs 27 which overlap are triangular in shape and the apexes of the tabs 27 come to a common point at the common point where the apexes of the triangular projections 26 meet.

With this type of shingle, 96 shingles are necessary per square; 150 square inches per shingle is exposed when laid as a covering; 96 nails per square are used per square to attach the covering to a surface; and the weight of a square of shingles when cut from standard weight asphalt-felt base material is 167 to 170 pounds approximately per square.

Each side of the hexagon of this species is seven and one-half inches, and the top and bottom of the hexagon is seven and one-half inches. The locking tabs 24 and 25 are spaced approximately twelve inches from edge to edge. The hexagon design on the roof is fifteen inches high and twelve inches wide.

It will be understood that the invention has been described for purposes of illustration and explanation and that changes and variations are possible without departing from the scope of the invention. All such modifications and changes are intended to be included in the appended claims.

I claim:

1. An interlocking shingle having upper and lower body portions, the lower portion being of

less width than the upper portion, a locking tab at each side of the bottom portion of the shingle, locking ledge portions on each side of the shingle between the upper and lower portions to receive the locking tabs of adjoining shingles when the shingles are assembled on a roof and said locking ledge portions extending outwardly and downwardly relative to said lower body portion to form wedging surfaces for the locking tabs to prevent removal of the locking tabs from the locking ledges, the edge of said locking ledge portions each extending outwardly to a point constituting the bottom side ends of said upper body portions; said ends then converging upwardly to form a locking tab at each side of said shingle, thence extending upwardly and outwardly for a distance greater than the upwardly converging portion and thence converging downwardly to form a locking tab at each upper side of said shingle and thence extending upwardly to form substantially a right angle with the top edge of the upper body portion.

2. An interlocking shingle having upper and lower body portions, the lower portion being of less width than the upper portion, locking tabs at each side of the bottom portion of the shingle, locking ledge portions on each side of the shingle between the upper and lower portions to receive the locking tabs of adjoining shingles when assembled on a roof, said locking ledge portions extending from their inwardly point outwardly and downwardly relative to said lower body portion to form wedging surfaces for the locking tabs to prevent removal of the locking tabs from the locking ledges, the lateral outwardly extremities of said locking ledge portions defining the bottom side ends of said upper body portions; said ends then converging upwardly to form a locking tab at each side of said shingle, thence extending upwardly and outwardly for a distance greater than the upwardly converging portion and thence converging downwardly to form a locking tab at each upper side of said shingle and thence extending upwardly to form substantially a right angle with the top edge of the upper body portion, the side walls of the lower portion of the shingle extending upwardly and outwardly to a point below the locking ledges, said side walls then extending upwardly and inwardly until reaching the locking ledge portions, the exposed area of said shingles when assembled on the roof giving a hexagonal design by the locking tabs fitting under the shingle to which it is attached and having a portion contacting the locking ledges which aligns the upwardly and inwardly extending portions on each shingle with the upwardly and outwardly extending portions of an attached shingle to form side walls of the hexagon.

3. An interlocking shingle having upper and lower body portions, the lower portion being of less width than the upper portion, a locking tab at each side of the bottom portion of the shingle, locking ledge portions on each side of the shingle between the upper and lower portions to receive the locking tabs of adjoining shingles when the shingles are assembled on a roof and said locking ledge portions extending outwardly and downwardly relative to said lower body portion to form wedging surfaces for the locking tabs to prevent removal of the locking tabs from the locking ledges, the edge of said locking ledge portions each extending outwardly to a point constituting the bottom side ends of said upper body portions; said ends then converging upwardly to form a locking tab at each side of said shingle, thence

extending upwardly and outwardly for a distance greater than the upwardly converging portion and thence converging downwardly to form a locking tab at each upper side of said shingle and thence extending upwardly to form substantially a right angle with the top edge of the upper body portion; said last mentioned locking tabs being triangular projections capable of overlapping on adjoining shingles below the locking ledge portions of adjoining shingles when shingles are assembled on a roof.

4. In a shingle cut from a single sheet and having an upper and lower portion; said upper portion being substantially rectangular in shape, said lower portion being of a width greater than its height, a locking tab at each side of the bottom portion of said shingle, said tabs each having an outer vertical edge with their respective top edges converging downwardly to join said lower portion, a locking ledge portion at each side of the bottom of the upper portion of said shingle and extending outwardly and downwardly relative to said lower portion, a locking tab on the outer end of each locking ledge portion, a notch in each of the two top corners of the upper portion of said shingle; said two lower corners of said upper portion each being less than that of a right angle, said lower portion having its two side edges each extending first downwardly and outwardly and then downwardly and inwardly.

5. An interlocking shingle having upper and lower body portions, a lower portion being of less width than the upper portion, a locking tab at each side of the bottom portion of the shingle, said tabs each having an outer vertical edge with their respective top edges converging downwardly to join said lower portion, locking ledge portions on each side of the shingle between the upper and lower portions to receive the locking tabs of adjoining shingles when the shingles are assembled on a roof and said locking ledge portions extending outwardly and downwardly relative to said lower body portion to form wedging surfaces for the locking tabs to prevent removal of the locking tabs from the locking ledges, the edge of said locking ledge portions each extending outwardly to a point constituting the bottom side ends of said upper body portions; said ends then converging upwardly to form a locking tab at each side of said shingle, thence extending upwardly and outwardly for a distance greater than the upwardly converging portion and thence converging downwardly to form a locking tab at each upper side of said shingle and thence extending upwardly to form substantially a right angle with the top edge of the upper body portion; said last mentioned locking tabs being triangular projections capable of overlapping on adjoining shingles below the locking ledge portions of adjoining shingles when shingles are assembled on a roof.
